J. D. GOODWIN.
SAFETY RAZOR.
APPLICATION FILED APR. 25, 1918

1,290,018.

Patented Dec. 31, 1918

UNITED STATES PATENT OFFICE.

JAMES D. GOODWIN, OF RICHMOND, VIRGINIA.

REISSUED

SAFETY-RAZOR.

1,290,018.

Specification of Letters Patent. Patented Dec. 31, 1918.

Application filed April 25, 1918. Serial No. 230,762.

To all whom it may concern:

Be it known that I, JAMES D. GOODWIN, a citizen of the United States, residing at Richmond, in the county of Henrico and State of Virginia, have invented certain new and useful Improvements in Safety-Razors, of which the following is a specification.

My invention relates to safety razors, the claims herein being limited to a part of the invention as illustrated and described in the application of Landon H. Stephenson and James D. Goodwin Serial Number 4245 filed Jan. 25, 1915. The object of the invention is to provide novel and improved means for the relative adjustment and fastening of the blade and handle at different angles to better adapt the article to the requirements and desire of the individual users.

With a view to attaining the foregoing object as will be understood from the description hereinafter following, taken in connection with accompanying drawings illustrating the preferred embodiment of the invention in certain novel features of construction, combination and arrangement of parts, is disclosed as follows:

In said drawings:—

Figure 1 is a side elevation of one form of my improved razor.

Fig. 2 is an end view of said improved form of razor looking toward the blade end with the clamping plate open and fragmentarily shown;

Fig. 3 is a cross sectional view on the line 3—3 of Fig. 2, through the complete razor but with the clamping plate partly open.

Fig. 4 is a cross sectional view on the line 4—4 of Fig. 1;

Fig. 5 is a side elevation;

Fig. 6 is a cross sectional view on the line 6—6 of Fig. 5;

Fig. 7 is a fragmentary cross sectional view taken on the line 7—7 of Fig. 6 through the complete razor;

Fig. 8 is a cross sectional view on the line 8—8 of Fig. 7, and

Fig. 9 is an enlarged detail sectional view of the blade carrier of the modified form of safety razor.

Referring specifically to drawings wherein like reference characters designate like or similar parts, and first to the device shown in Figs. 1 to 4 inclusive, a razor blade holder is shown which comprises a guard plate 1 which is pivoted at 2 to a fastening plate or clamping plate 3. The razor blade 4 is se-

cured in position by the clamping plate 3. At each end of the blade 4 a notch 4' is provided into which extends a lug 1' integral with and rising from the guard plate. As 60 means to secure the clamping plate 3 in blade-fastening position, I employ a slideable locking plate 5 which has elongated slots 6 through which pass pins 7 secured to the plate. This slideable member 5 has an 65 upwardly and inwardly extending fastening lug 8 which enters a groove 9 formed in the top of the fastening plate 3. It will be realized that by this construction, the plate 3 is fastened by the slideable fastening element 70 5. When the blade is to be removed, the element 5 is moved outwardly to the position shown in Fig. 2, the sliding movement being permitted by the elongated slots 6. After the lug 8 through sliding movement 75 disengages the plate 3, said plate can then be freely swung upwardly from the pivot 2 and the blade inspected or removed if desired, as suggested in Figs. 2 and 3.

A suitable fastening head 10 preferably 80 having a spherical surface as shown, is secured to the holder by means of a stud 11 integral with the head 10 and fastened in an opening provided in the guard plate 1. Upon the stud 11 as an axis is mounted a 85 swivel plate 12 which has ears 13 to which the handle is pivoted for movement in planes diametric with the axis of stub 11. While the handle may be of any approved form, I prefer to construct it so that it will have 90 separate arms 14 which are hinged on pins in the nature of set screws 14', which set screws pass through the arms and detachably engage screw threads in openings in the lugs 13. The handle may be an integral 95 structure composing the arms 14 and bearing blocks 15 and 16, strips 17 intermediate the bearing blocks and a suitable shaped end strip 18. Block 15 has an opening 19 as seen in Figs. 3 and 4, which is provided 100 with screw threads to engage the screw threads of a fastening rod 20 and 21. Rod 20 has an enlarged portion 22 which is turnably and slidably mounted in an opening 23 of block 16. Beyond the block 16 is provided a head 20' preferably knurled on its periphery as shown, the inner end of the rod 20 is preferably reduced or tapered at 24 so as to better engage recesses 25 extending inwardly from the periphery of the head 10 and arranged in any approved manner 110 for instance in a peripheral row and one sub-

stantially opposite the axes of the set screws 14', as shown. It will be realized that the handle has substantially a universal joint connection with the blade holder in view of the stud 11 and set screws 14'.

5. While rod 20 is in a retracted position with the end 24 disengaged from the notches 25, it will be realized that the handle can freely turn from the stud 11 as an axis 10 and that in paths radially of the stud 11. In this way the handle can be adjusted to practically any desired angle, so as to adapt the safety razor to the needs and desires of the individual users. The handle may be 15 fastened in any of the adjusted positions upon screwing the rod 20 by engagement of the fingers of the operator with the head 20' so that the end 24 will frictionally engage or bite into the head 10. However, it is 20 preferred to provide the recesses 25 at the proper location so that it will not be necessary to depend upon friction alone to maintain the parts in adjusted position. In order to properly adjust the handle, head 20' 25 is turned in a direction opposite to that mentioned, so as to retract the rod 20 so that the end 24 will disengage the notches 25.

30. A modified form of the invention is illustrated in Figs. 5 to 9 inclusive. The blade holder in this instance comprises a guard plate 30 having eyelets 31. A removable blade 32 is fastened against the plate 30 by means of a fastening plate 33 which has a hook 34 extending toward the handle and 35 provided with an inwardly extending lug or lip 35. A latch 36 is employed to engage the clamping plate 33 intermediate the lug 35 and the guard plate 30 to facilitate its adjustment. The blade 32 is mounted against 40 sliding movement relatively to the guard plate by means in the nature of lugs 37 integral with the plate which projects into an elongated slot 38 of the blade. Extending toward the handle at an angle to and integral 45 with the fastening plate 33 is a hinge leaf 39 having side ears 40 through which and through the eyelets 31 of the guard plate 30, a pivot member of pintle 42 is passed to pivotally connect the clamping plate 33 to the 50 guard plate 30. A blade carried in the form of a clasp is pivotally mounted on the pintle 42 by means of an eyelet 43 through which the pintle 42 passes and which eyelet is riveted intermediate the ears 40 of hinge leaf 39 55 to prevent undue lateral movement of the guard. Extending from the eyelet 43 tangentially and forming the remainder of the clasp are two slightly separated spring clasp arms 44, whose tendency is to spring toward 60 each other. It will be realized that the eyelet and arms 44 compose an integral structure. One arm 44 is struck upwardly to form a socket 44', and the other arm is struck upwardly to form a lug 44'', which extends 65 into the end notch 32' of blade 32 to prevent

accidental lateral movement of the blade, especially when the blade is raised. The blade 32 is adapted to be inserted intermediate the clasp arms 44 so as to be frictionally engaged by the arms and carried thereby. While no 70 blade is fastened in place, the clasp or carrier at all times holds the blade as may best be seen in Fig. 7.

Adjacent the hinge end, guard plate 30 is 75 provided with a recess 45 in its upper surface to receive one of the clasp arms 44 in order that the blade 32 may lie flat on the upper face of plate 30. The arms 44 are located in the path of movement of the end 80 46 of the hinge leaf 39. Secured in an opening of the plate 30 is a stud 47 which has a fastening head 48 thereon provided with a spherical surface. The latch 36 is mounted on the stud 47 to swing in a plane parallel to that of the head 30.

85. It will be noted that the latch 36 by its engagement between lip 35 and the plate 30 securely fastens the clamping plate 33 over the blade 32 and that the lugs 37 extend into the recess or elongated slot 38 securely fastening the blade to the guard 30. Further it 90 will be noted that at all times while the blade 32 is fastened, it is held by the carrier of clasp 43 and 44. In order to remove the blade, latch 36 by engagement of the fingers 36' is moved laterally to disengage the lip 35, whereupon the lip 35 may be moved away from the guard 30. During the movement 95 of the clamp plate 33, end 36 of hinge leaf 39 engages against one of the clasp arms 44, thereby causing the clasp 43-44 to move with the clamp plate 33 and causing the blade 32 to separate or move away from the guard 30. It will be realized that inasmuch as the 100 blade 32 is then separated from the guard 30, that it can be more easily removed from the holder than would be true if it rested at all times upon the upper face of the guard 30. It is to be noted that the clamp plate 33 has a limited movement before the end 46 105 engages the blade carrier which is for the purpose of preventing the blade 32 closely following the clamp plate 33. Attention is called to the fact that when the clamp plate 33 first engages the blade, the under surface 110 of the clamp plate at its sides first engages the end of the blade near the pivot 42, so that the clamp plate will first assume the position shown in Fig. 5 in dotted lines. As the blade is flexible, this clamp plate can be 115 pressed downwardly so that the hook 34 will extend through a recess 49 in plate 30 in order that the latch 36 may engage the hook. In view of the fact that the blade is tensioned while fastened upon the disengagement 120 of the latch 36 with the lip 35, the clamp plate will immediately spring upwardly through the action of the blade to the dotted line position shown in Fig. 5 so that it may be more readily manipulated. A 125 130

swivel 50 is turnably mounted in the screw stud 47 and between the swivel and latch 36 may be interposed a washer 51 if desired. The swivel is provided with angle lugs giving it substantially the form of a yoke, and which lugs are designated 52 and have pivotally connected thereto, by means of set screws 53, arms 54 of the handle. These arms 54 are preferably formed integral with 10 a bearing body 55 suitably shaped to form the handle proper which may have at its outer end a suitable shaped strip 56 integral therewith. A fastening rod 59 is employed which is provided with screw threads at 15 60 to mesh with screw threads provided in an opening 61 of body 55. On the rod 59 is provided a clutch member 62 to directly engage the head 48 at the end opposite to clutch head 62. The rod 59 is provided with 20 a manipulating head 63 preferably knurled on its exterior.

The handle 54—55—56 is freely turnable by means of the swivel 50, on the stud 47 and in addition is freely turnable in planes radially of the stud 47 as an axis on the pivots 53. When the handle is swung the rod 59 is of course out of clutch relation with the head 48. After proper adjustment has been secured, the rod is screwed inwardly so that

the clutch plate 62 will engage the curved 30 exterior surface of the head in order to fasten the parts in relative adjusted relation.

It is to be understood that inasmuch as I have shown only the preferred embodiment of my invention, changes in detail of construction, arrangement and combination of the parts may be resorted to without departing from the spirit and scope of the invention.

Having thus described my invention what 40 I claim is:—

An edge tool having a holder member, a handle member thereof, said handle having separate arms at one end and an opening extending therethrough in the opposite end, a 45 swivel having ears, the said arms being pivoted to said ears, a head, a stud on which said swivel is mounted connected to said head and to said holder, said head having a threaded opening extending longitudinally 50 therethrough, and a screw rod in said opening and having one end adapted to engage the head, and an operating nut carried by the rod opposite the opening, whereby the nut can be turned for operating the rod. 55

In testimony whereof I affix my signature.

JAMES D. GOODWIN.
